UNITED STATES PATENT OFFICE.

JOSEPH P. FLEMING, OF WORCESTER, MASSACHUSETTS, ASSIGNOR TO WAKEFIELD ALL-STEEL WRENCH COMPANY, INC., OF WORCESTER, MASSACHUSETTS, A CORPORATION OF MASSACHUSETTS.

RETAINING DEVICE.

Application filed September 17, 1926. Serial No. 136,167.

The present invention relates to a containing and retaining device for a plurality of similarly shaped objects, as for instance, a set of socket wrenches of graduated size, 5 where a common handle or shank is provided for use, selectively, with any one of said socketed members.

Heretofore considerable difficulty has been encountered in the provision of a compact and inexpensive container for a wrench set of the above described type, or for any similar set of articles of graduated size. The present invention obviates this difficulty by the novel construction and arrangement of 15 parts hereinafter set forth, in which the common handle or shank is utilized as a retaining means for all of the articles,—and while I have chosen to show my invention in connection with a socket wrench set, it 20 will be understood that this showing is merely by way of example, and that the invention could as well be applied to a variety of other devices and objects within the scope of the appended claims.

25 In the accompanying drawings, which illustrate said invention,—

Fig. 1 is a view in side elevation, partly in section, of one of the members of a socket wrench set, shown in conjunction with the 30 detachable handle or shank that is common to all of the socketed members of said set.

Fig. 2 is a plan view, showing the assembly of all the socketed members of the set in the containing and retaining devices of 35 my invention.

Fig. 3 is a side elevation of the parts shown in Fig. 2.

Fig. 4 is an end elevation of said parts.

Fig. 5 is a detached view of a holding 40 clamp.

Fig. 6 is a view in side elevation, showing the assembly of a modified form of the invention, embodying a ratcheting device for the set of socket wrenches.

Fig. 7 is a sectional view, showing the use 45 of such ratcheting device.

Fig. 8 is a section on the line 8—8 of Fig. 6.

Like reference characters refer to like 50 parts in the different figures.

A socket wrench set of the type referred to provides, as is well known, a plurality of similarly shaped members 1, 2, 3, 4, 5, 6, 7 and 8, graduated in size, and each having

a nut or bolt-receiving socket, here shown 55 as hexagonal in form, and adapted to fit a given size of nut or bolt, ranging from a large bolt or nut, for which the member 1 is provided, to a small bolt or nut, for which the member 8 is provided, with all intermediate sizes taken care of by the members 60 2 to 7 inclusive. The sockets of these members are not only graduated as to internal diameter or area, but also as to depth, and consequently the members themselves 65 ordinarily vary in thickness or height, the large member 1 of the set, as shown in Fig. 3, being considerably higher than the smallest member 8. As is the usual practice, each member 1 to 8 inclusive of the set provides, 70 at the rear of its socketed nut-engaging portion, a polygonal opening 9, all of the openings 9 being of the same size and shape, so as to be operatively engaged by a similarly shaped portion of a single handle member 75 10, common to all of the socket members.

As here shown, the openings 9 are hexagonal, and the handle member 10 is of hexagonal section to fit all of said openings 9. As shown in Fig. 1, one end of the shank or 80 handle 10 is bent at right angles, as indicated at 11, and one face of said bent end provides the usual spring pressed ball 12, which frictionally engages a face of the opening 9 to hold the socket member on the 85 handle, thus to provide the wrench assembly shown in said Fig. 1. Or, if desired, the selected socket member may be operatively attached in the same way to the other end of handle 10 by means of the spring 90 pressed ball 13, thereby to provide a wrench assembly which is better adapted to the reaching of inaccessible bolts or nuts, using the bent end 11 as a lever arm. It will be understood, of course, that any one of the 95 socket members 1 to 8 inclusive may be operatively attached to either end of the handle 10, as desired,—making a total, in the present instance, of sixteen different wrench assemblies or combinations.

According to the invention, as shown in Figs. 2, 3 and 4, I provide a shallow tray 14, adapted to receive the wrench members 1 to 8 inclusive in a row, said tray preferably being made from a single elongated 100 piece of sheet metal, bent up at its longitudinal edges to provide side walls 15, 15, which converge toward each other in con-

formity with the gradually decreasing diameters of the members 1 to 8 inclusive, so that said members fit snugly between said walls throughout the entire row. The end wall 16, at the large end of said tray, is preferably curved to conform to the shape of the large socket member 1, and the end wall 17, at the other end of said tray, is preferably curved to conform to the shape 10 of the small socket member 8.

According to the invention, the handle 10 is utilized, in a novel manner, to hold all the members 1 to 8 inclusive in the tray 14. As shown in Fig. 3, the length of the bent portion 11 of said handle is just sufficient to permit the handle to clear the rim of the bolt-engaging socket of large member 1 when said bent portion 11 is introduced to the opening 9 of said member through said bolt-engaging socket, instead of from the rear, in the operative manner shown in Fig. 1. When the hexagonal bent end 11 of the handle is thus inserted reversely in the opening 9 of member 1, the elongated overhanging portion of the handle 10 will overlie the entire row of socket members 1 to 8 inclusive in the tray 14, as shown in Figs. 2 and 3,—the handle 10 being made of sufficient length for this purpose,—and the bend of the handle 10 preferably being very slightly less than a right angle, so that said elongated portion when in this overlying position will be tipped down substantially into contact with the smaller socket members of the set which, as heretofore stated, are generally of less height than the larger members.

With the handle 10 in the above described position, where it serves as a common holding means to all of the socket members 1 to 8 inclusive to retain them in the tray 14, the assemblage of the entire wrench set in a compact form is completed by encircling the tray 14 and handle 10 with a clamping member 18 of the form shown in Fig. 5, this member slipping loosely over the small end of the tray 14 and the overlying end portion of handle 10, and being of sufficient size so that it can be pushed along longitudinally 50 to a point substantially midway of the handle, where it binds the upper surface of said handle and the gradually diverging side walls 15, 15 and bottom 14 of the tray, thereby to hold the handle 10 down firmly to prevent any relative movement of separation between said handle and said tray. This binds all the parts together against displacement, the handle, in conjunction with the clamp 18, serving to hold all the members 1 to 8 inclusive securely in the tray, and doing away entirely with the necessity for an awkwardly shaped box for the parts, in which they would inevitably rattle around and become misplaced.

65 In the modified form of the invention

shown in Figs. 6, 7 and 8, the socket members 1 to 8 inclusive are adapted to be assembled in a tray 20, of the same general form as the tray 14 of Figs. 2 and 3. The assembly here includes, in addition to the usual handle 10, a ratcheting device or handle 21 of the usual construction, adapted for use selectively with any one of the socket members 1 to 8 inclusive of the set. As shown in Fig. 7, the member 21 provides a ratchet 22 which is operatively engaged by a pawl 23, said ratchet 22 having an hexagonal opening therethrough for the entrance of a similarly shaped extension number 24, whose end, like the ends of handle 10, is adapted to be operatively engaged with any one of the socket members 1 to 8 inclusive. Thus is provided a ratcheting attachment for all of the socket wrench members, and it is to be noted further that the opposite end of extension 24 provides a screw driver blade 25, so that the set also affords a ratcheting screw driver.

The assembly of these various parts in a compact form is effected in the manner shown in Figs. 6 and 8, where the extension member 24 is inserted in the opening 9 of the large socket member 1, with its screw driver end 25 projecting up through the hole of ratchet 22, so that the ratchet handle 21 overlies the row of socket members 1 to 7 inclusive, but leaves the smallest socket member 8 exposed. Into this smallest socket member 8 is inserted the bend end 11 of handle 10, so that the shank of said handle, as shown in Fig. 6, overlies the ratchet handle 21. A suitable clamping device 26 is adapted to encircle this assembly from the small end of tray 20, and as shown at 27, a portion of the bottom of tray 20 is pressed or stamped outwardly to form an integral elongated loop, for receiving the bottom of the clamping device 26 and preventing its separation or loss from the tray when moved into inoperative position, as shown by broken lines in Fig. 6. To level up the bottom of the tray, a similar stamped out portion 28 is preferably formed also at the larger end thereof.

115 I claim,

1. The combination with a plurality of apertured members of graduated size, of a tray adapted to receive said members in a row, a handle fitting the apertures of all of said members and adapted, selectively, for use with any of them, the end of said handle being bent so that when inserted in the aperture of the larger of said members, the remaining portion of said handle will overlie the remaining members of said row, conforming itself to the decreasing size of the latter, and a detachable encircling member of sufficient size to be entered loosely by said handle and tray at the small end of the row, and adapted, when moved to a point 120

125

130

intermediate the ends of said row, to clamp said parts together.

2. The combination with a plurality of apertured members of graduated size, of a tray adapted to receive said members in a row, a handle fitting the apertures of all of said members and adapted, selectively for use with any of them, the end of said handle being bent at an angle slightly less than 90° to the main portion thereof, so that when inserted in the aperture of a larger member the remaining portion of such handle will overlie the remaining members of said row conforming itself to the decreasing size of

the latter, and a link to connect the top of 15 said handle with the bottom of said tray, whereby it may be forced over said handle and said tray from that end of the latter which contains the smallest apertured members; and when forced to a given point along 20 said handle, will by a wedging action, owing to the gradual increase in distance between the bottom of said tray and the upper surface of said handle, firmly hold the handle against the apertured members. 25

Dated this 13th day of September 1926.

JOSEPH P. FLEMING.
